LISTING APPARATUS

Harry K. Jensen, Oakland, Calif.

Application August 23, 1938, Serial No. 226,291

7 Claims. (Cl. 164—111)

This invention relates to improvements in listing apparatus and, more particularly, to a combined memorandum and listing device.

Among the objects of the invention is to provide a mechanical indicator serving as a memorandum for the purchase of commodities, such as groceries, which will deliver a punched list of the items desired.

Another object is to so design the apparatus that it may be produced entirely from sheet metal stampings at very low cost.

Another object is to provide simple means for feeding the lists to be punched into proper registry with the punching means.

Other objects and advantages appear as this description progresses.

In this specification and the accompanying drawing, the invention is disclosed in its preferred form. It is to be understood, however, that it may be embodied in other forms within the purview of the claims following the description.

In the one sheet of drawings:

Fig. 1 is a front elevation view of a listing apparatus constructed in accordance with the present invention.

Fig. 2 is a vertical section of the same taken along the line II—II in Fig. 1.

Fig. 3 is a horizontal section of the same taken along the line III—III in Fig. 1.

Fig. 4 is an enlarged fragmentary detail view in vertical section showing the list punching means.

Fig. 5 is a detail view in perspective of one of the punches.

Fig. 6 is a transverse vertical section taken along the line VI—VI in Fig. 2 and showing the details of the lower portion of the casing.

Fig. 7 is a plane view, in somewhat reduced scale, of the lower portion of a punched list, the preceding list being shown in dotted lines.

In detail, the construction illustrated in the drawing comprises the sheet metal casing having the back 1 which can be conveniently fixed to the wall or to a suitable bracket by the thumbtacks 2, 3 driven through holes provided in the back 1. The sides 4, 5 (see Fig. 3) are bent inwardly from the back 1 and then bent inwardly to form the flanges 6, 7 overhanging the back 1. The lower portion of the back 1 is bent inwardly to form the strut 8 which abuts the tongues 9, 9 struck inwardly from the flanges 6, 7 to increase the stability of the structure.

The front of the casing is closed by the cover 10 having the lateral flanges 11, 12 snugly fitting over the sides 4, 5. The cover pivots on the studs 13, 14 which extend through its flanges 11, 12 and the sides 4, 5 of the casing. When closed, the cover is maintained in position by friction.

The continuous strip of paper x is cross-per-

forated at intervals as at Y, see Fig. 7, and has manifold commodity lists printed thereon intermediate the perforations. The several items are preferably arranged alphabetically in a double row as indicated in Fig. 7. Trade names and other advertising can be associated with the various items. The printed strip x is folded back and forth on the perforations Y to form a compact bundle for insertion in the present device.

The cover 10 is swung outward on its pivot 13, 14 to permit the entry of the folded strip x between the back 1 and the flanges 6, 7. The removable sheet metal guide 15, when placed in position, is supported by the lugs 16 upset therefrom which engage under the upper edges of the flanges 6, 7. One end of the paper strip x is drawn over the guide 15 and then downwardly to the lower end of the flanges 6, 7, as at A. When the cover 10 is closed, the length A of the paper strip is confined between the cover and the flanges 6, 7 of the casing.

The cover 10 has the upset channels 17, 18 therein extending adjacent the edges of the underlying length A of the paper strip. The series of punches 19—19 have their bodies disposed in the channels 17, 18 and have the acute bends 19' therein which extend outwardly through the equidistantly spaced holes 20—20 provided in the channels. The bends 19' terminate in the tangential flat portions 19'' with the adjacent reverse curves 19''' having the trips 19x 30 extending outwardly therefrom. The arrangement of the acute bends 19' and the contiguous tangential portions 19'' is such that the punches 19 cannot be displaced from their confining holes 20 when the cover 10 is opened.

The body of each of the punches 19 terminates in the angular nose 21 best shown in Fig. 5. Registering with each of the plurality of punches are the series of triangular slots 22, 22 in the flanges 6, 7 of the casing. Pushing any of the trips 19x inwardly swings the punch on its pivot 19'—20 and forces its angular nose through the registering triangular slot 22, thus punching the sheet A as indicated in Fig. 4 to form an angular line of severance.

The cover 10 has the list 24 of commodities thereon, the various items of which correspond to the items printed on the sheet A. When the need for replenishing various commodities is discovered, the appropriate trips 19x are pressed inward, punching the printed sheet A adjacent the items desired. After a trip 19x is operated, its depressed condition serves as a memorandum that the need for the corresponding commodity has been listed.

It is important that the printed sheet A assume a predetermined position in the device in proper registry with the punches 19. This is effected by the following means: The lower end 60

of the cover 10 has the sprags 25, 26 indented therein. The spring fingers 27, 27 on the flanges 6, 7 urge the sheet A into operative engagement with the sprags. At each of the perforations Y 5 the strip x has the pair of holes 2 therein which are adapted to be entered by the sprags 25, 26 which abut the upper edges of the holes to prevent further downward movement of the sheet A. When the sprags 25, 26 are thus engaged in the holes Z, the items on the sheet A are in proper 10 registry with the punches 19.

The lower edge of the cover 10 has the recess 29 therein to permit the sheet A to be grasped by the fingers of the user. When it is desired 15 to go to the market for the purchase of the listed commodities, the lower end of the sheet A is grasped and pushed inward slightly. This releases the edges of the holes Z from engagement with the sprags 25, 26. The sheet A is then 20 pulled downward. The spring fingers 27, 27 restore the sheet into engagement with the sprags 25, 26. When the succeeding pair of holes Z 25 engage the sprags, further withdrawal of the sheet is prevented. At this juncture, the perforations Y are aligned with the lower edge of the cover 10, thus enabling the punched sheet A to be readily detached from the remainder of the strip x by tearing along the perforations Y 30 in an obvious manner.

When the punched sheet A is withdrawn, it 35 will be apparent from examination of Fig. 4 that the tripped punches 19 will be automatically restored into inoperative position in readiness for another punching operation on the succeeding sheet. The withdrawal of the sheet will also cause the angular tongues severed by the punches 21 to catch on the slots 22. The continued withdrawal of the punched sheet will then fold the tongues backward to form triangular openings 40 adjacent the items desired.

Having thus described this invention, what I claim and desire to secure by Letters Patent is:

1. An apparatus of the class described comprising a casing having a series of slots therein; a continuous paper strip having manifold lists 45 of items printed thereon and adapted to be contained in said casing; means for bringing a portion of said strip into a position overlying said slots; individual punches in operative relation 50 to said slots and arranged to be selectively tripped to punch said strip; and means for permitting the withdrawal of the punched portion of said strip; said punches being so arranged 55 that the tripped punches are automatically restored by the withdrawal of the punched portion of said strip.

2. An apparatus of the class described comprising a casing having a series of interspaced slots therein; a continuous paper strip having 60 manifold lists of items printed thereon and adapted to be contained in said casing with a portion of the strip overlying said slots; the items on said strip being arranged so as to register with said slots; individual punches in operative relation to said slots and the overlying portion of said strip and adapted to be selectively tripped to punch said strip; a list of items identifying said punches and corresponding with the items printed on the list overlying said slots; 65 and means for withdrawing the punched portion of said strip; said punches being so arranged that the tripped punches are automatically restored by the withdrawal of the punched portion of said strip.

3. An apparatus of the class described comprising a casing having a series of interspaced slots therein; a cover pivoted on said casing and adapted to overlie said slots; means for passing a paper strip having a list of items printed thereon between said cover and said slots; and a series of individual punches pivoted on said cover and adapted to cooperate with said slots to punch said paper strip. 5

4. An apparatus of the class described comprising a casing having a series of interspaced slots therein; a cover mounted on said casing, adapted to overlie said slots, and having a channel therein opposite said series of slots; said cover having a series of holes therethrough communicating with said channel and each located near one of said slots; means for passing a paper strip between said cover and said slots; and a series of punches lying in said channel in operative relation to said slots, pivotally engaging the holes 20 in said cover, and having a manually operable trip portion extending beyond said cover.

5. An apparatus of the class described comprising a casing having a series of interspaced slots therein; a cover pivoted on said casing, 25 adapted to overlie said slots, and having a series of holes therethrough communicating with said channel and each located near one of said slots; means for passing a paper strip between said cover and said slots; and a series of punches lying 30 in said channel in operative relation to said slots, each having an acute bend therein pivotally engaging one of the openings in said cover, and having a manually operated trip portion extending tangentially outward from said acute bend; 35 said holes, acute bends, and tangential extensions being so arranged that said trips cannot be displaced from said holes when said cover is swung outward from said casing.

6. An apparatus of the class described comprising a casing having a series of interspaced slots therein; a cover mounted on said casing and adapted to overlie said slots; a continuous paper strip having perforations thereacross at intervals 45 and holes adjacent said perforations; said casing being arranged to contain said strip and have one end of said strip brought between said casing and cover across the slots in said casing; punches on said cover in operative relation to said slots and arranged to be selectively tripped 50 to punch said strip; means permitting the manual grasping of said end of the strip; and a sprag on said cover adapted to engage the holes in said strip. 55

7. An apparatus of the class described comprising a casing having a series of interspaced slots therein; a cover mounted on said casing and adapted to overlie said slots; a continuous paper strip having manifold lists of items printed thereon, perforations thereacross at intervals, and holes adjacent said perforations; said casing being adapted to contain said strip and have one end of said strip brought between said casing and cover across the slots in said casing; punches on said cover in operative relation to said slots 60 and arranged to be selectively tripped to punch said strip; said cover having a recess therein to permit the manual grasping of said end of the strip; a sprag on said cover adapted to engage the holes in said strip to limit its manual withdrawal from said casing; and a spring finger on said casing urging said strip into operative engagement with said sprag. 65
